UNITED STATES PATENT OFFICE.

EDWARD WILLIAM HENSTOCK, OF CHESTER, ENGLAND.

PEDAL FOR VELOCIPEDES.

SPECIFICATION forming part of Letters Patent No. 700,492, dated May 20, 1902.

Application filed July 17, 1900. Serial No. 23,924. (No model.)

To all whom it may concern:

Be it known that I, EDWARD WILLIAM HENSTOCK, medical student, a subject of the Queen of Great Britain, residing at Drayton Villa, Lumley Road, Liverpool Road, Chester, in the county of Chester, England, have invented certain new and useful Improvements in Pedals for Velocipedes, of which the following is a specification.

10 This invention relates to velocipede-pedals capable of being folded up against or toward the pedal-crank when not required for use.

According to this invention that part of the pedal on which the foot bears may be of the usual or any suitable construction and mounted with ball-bearings in the usual or any other suitable manner on the pedal shaft or spindle, the inner end of which latter is hinged or hinge-jointed to the outer end of 15 the pedal-crank, as hereinafter described, and capable of folding inward toward the crank, while the outward movement is prevented beyond a certain point, as hereinafter described, a special locking device being provided to lock and firmly secure the pedal-shaft rigidly in position for use—i. e., at right angles to the crank—this same locking device also serving to hold the pedal in the folded 20 position.

30 In the accompanying drawings, Figure 1 shows a crank and a pedal-shaft hinged thereto according to the present invention, the pedal being arranged at right angles to the crank in position for use. Fig. 2 shows the 35 pedal-shaft turned upon its hinges toward the crank. Fig. 3 shows the pedal folded up on its hinge and laid close against the crank—that is to say, in position to which the same can be moved when out of use. Figs. 4 to 7, 40 inclusive, show a slightly-modified construction, in which Fig. 4 is a rear view, Fig. 5 a front view, Fig. 6 a side view, of the crank of the hinged pedal supposed to be in position for use; and Fig. 7 is a similar view to Fig. 45 6, showing the position when the pedal is out of use.

In carrying out the present invention the inner end of the pedal-shaft C may either be screwed into or otherwise secured to a boss 50 or enlargement D or may be integral with said enlargement or boss D on its inner end, this latter being hinged at E to the crank A

a little distance from the outer end A' of the latter. The part of said boss or enlargement D outermost from the hinge-joint E is formed 55 with shoulders A^x, adapted to fit against the face B^x of the end A' of the crank A when the pedal is in lowered position for use, and this boss or enlargement D is also formed with a tongue, block, or other corresponding part 60 or projection F, and hereinafter referred to as a "snug," said snug being adapted to fit snugly and exactly in a longitudinal slot or recess A², hereinafter referred to, and the second slot adapted to receive the same and located in the outer end A' of the crank A at an angle to the first slot H, hereinafter described, when the pedal is in its normal lowered position, as in Fig. 1, and to thereby limit the outward swing of the pedal-shaft C 65 and at the same time assist in holding the same rigidly in position for use. In this snug F a slot G is provided in a line parallel with the longitudinal axis of the hinge-pin E, and a corresponding or other suitable slot H is 70 provided in the outer end A' of the crank A, these slots G and H being adapted to exactly register and coincide when the pedal is in position for use at right angles to the crank, as shown in Figs. 1 and 6, respectively, whereupon the locking device or bar I, hinged at J, is inserted in the said two slots G H, 75 which slots it exactly fits, and thereby retains the pedal-shaft firmly and rigidly in position, this locking-bar I being hinged in the slot H 80 in the crank extremity A' and provided with a screw-threaded projection I' on its free end, on which a nut I^x is screwed to lock and hold said bar I in the said two slots G H when the latter coincide. It is evident that the locking device or bar I may be fixed in position 85 in any other suitable manner.

When the pedal is folded in the position shown in Fig. 3, it is locked and held in this position by replacing the bar I in the slot H, 90 which thereby engages with the innermost extremity of the boss or enlargement D—in other words, the end of the snug F.

The bar I should be made of the exact size and shape of the slots H G, so that when the pedal is in the position shown in Figs. 1 and 6 the end of the crank is practically solid and the weakening effect caused by the hinged pedal reduced to a minimum.

In Figs. 4 to 7 only a slight modification is shown—that is to say, the configuration, shape, or design of the adjacent portions of the crank and pedal-shaft is different from the other figures—the mechanical construction, however, being the same as in the latter and the details being somewhat clearer.

The essential feature of the present invention consists, therefore, in the special construction and fitting together of the pedal-spindle end and the bifurcated crank end and the cross-cut formed by the slot G in the pedal-spindle and the transverse slot H in the bifurcated crank and the locking-bar I, adapted to fit accurately in said slots G H when in alinement, and thus form a practically solid crank end.

Having thus described my invention, what I claim as new, and desire to secure by Letters Patent, is—

1. The combination, with a crank and a pedal-shaft pivoted to the outer end of the same, said crank having a longitudinal slot in its outer end and a second longitudinal slot at an angle to the first and in the plane of movement of the pedal-shaft, of a snug projecting from said pedal-shaft and entering the said second slot, a slot in said snug registering with the first-named slot of the crank when the shaft is in lowered position, a lock-

ing-bar pivoted at one end to one side of the crank and adapted to swing in the first slot across the second, a screw-threaded projection on the opposite end of the locking-bar, and means for connecting said projection with the crank, substantially as set forth.

2. The combination, with a crank and a pedal-shaft pivoted to the outer end of the same, said crank having a longitudinal slot in its outer end and a second longitudinal slot at an angle to the first and in the plane of movement of the pedal-shaft, of a snug projecting from said pedal-shaft and entering said second slot, a slot in said snug registering with the first-named slot of the crank when the shaft is in lowered position, a locking-bar pivoted at one end to one side of the crank and adapted to swing in the first slot across the second, a screw-threaded projection on the opposite end of the locking-bar and projecting beyond the side of the crank, and a locking-nut on said projection, substantially as set forth.

In witness whereof I have hereunto set my hand in presence of two witnesses.

EDWARD WILLIAM HENSTOCK.
